UNITED STATES PATENT OFFICE.

JOSEPH KENNARD KOONS, OF MONTGOMERY, PENNSYLVANIA.

BOLT-MACHINE.

No. 811,411.

Specification of Letters Patent.

Patented Jan. 30, 1906.

Application filed October 6, 1904. Serial No. 227,231.

To all whom it may concern:

Be it known that I, JOSEPH KENNARD KOONS, a citizen of the United States, residing at Montgomery, in the county of Lycoming and State of Pennsylvania, have made certain new and useful Improvements in Bolt-Machines, of which the following is a specification.

My invention is a machine for use in making bolts, set-screws, and the like; and the invention consists in certain novel constructions and combinations of parts, as will be hereinafter described and claimed.

In the drawings, Figure 1 is a top plan view, and Fig. 2 is a front elevation, of a machine embodying my invention. Fig. 3 is a vertical longitudinal section thereof drawn alongside the feed-screw and the main shaft. Fig. 4 is a cross-section on about line 4 4 of Fig. 3. Fig. 5 is a detail perspective view showing the devices for turning the stock down and for cutting the thread thereon. Fig. 6 is a cross-section on about line 6 6 of Fig. 3. Fig. 7 is a cross-section on about line 7 7 of Fig. 3. Fig. 8 is a detail longitudinal section of one of the tubes of the gripping-blocks and devices for operating the same for holding the stock-rod against longitudinal movement. Fig. 9 is a cross-section on about line 9 9 of Fig. 8. Fig. 10 is a side view, and Fig. 11 is an elevation, of the inner side of one of the gripping-blocks. Fig. 12 is a detail elevation of the device for holding the stock-rods and for feeding the same longitudinally. Fig. 13 is a cross-section on about line 13 13 of Fig. 12. Fig. 14 is a cross-section on about line 14 14 of Fig. 13. Fig. 15 is an elevation of the device for throwing the nut-sections into and out of mesh with the feed-screw. Fig. 16 is a detail cross-section showing the sectional construction of the outer gear used in setting the devices for adjusting the gripping-blocks to hold the stock-rods. Fig. 17 is a cross-section on about line 17 17 of Fig. 3. Fig. 18 is a cross-section on about line 18 18 of Fig. 3. Fig. 19 is a detail section on about line 19 19 of Fig. 17. Fig. 20 is a detail section on about line 20 20 of Fig. 19. Fig. 21 is a detail perspective view showing the different parts of the cutting-off tool detached, and Fig. 22 is a detail perspective view of the cutting-off tool with the parts assembled.

By my invention I provide, in connection with a main shaft A and a frame having slides B, along which some of the movable

parts are arranged to slide, devices for feeding the stock-rods C, from which the bolts are cut, forwardly to the tools for turning down such stock-rods and for threading the same and devices for cutting off the stock-rods after the same have been formed into the bolts or set-screws, as will be described.

The shaft A may be turned by any suitable gearing, preferably by gearing similar to that of a lathe and not shown herein because it forms no part of the present invention.

The tool-head D, carrying devices for turning down the stock-rods and for threading the same, has a base D', sliding along the frame-slides B, and which may be moved along said slides by suitable gearing, as best shown in Fig. 4, with a rack b on the frame. Such gearing may be of suitable construction and may be operated from a hand-crank d to move the head D back and forth along the frame. This tool-head D includes a body D² and end plates D³ and D⁴, which extend outwardly beyond the body D² and have openings at d⁵, in which turn the shafts D⁶, carrying the cutters D⁶ and D⁷, which are arranged eccentrically to the shaft D⁶ and are carried by a cutter head or disk D⁸ at one end of said shaft and working against the inner face of the head D.

The cutter D⁶ may be similar to that of an ordinary bolt-mill or box-tool adapted to turn down the rod to the desired diameter, while the cutter D⁷ is an ordinary thread-cutting die, and these cutters D⁶ and D⁷ are secured in suitable sockets d⁸ in the head D⁸ and may be secured therein by clamping-screws d⁹, as will be understood from Fig. 5 of the drawings.

At the end opposite the disk D⁸, with its cutters D⁶ and D⁷, the shaft D⁶ is provided with a pinion D⁹, which by means of suitable gearing co-operates in turning the shaft D⁶ to set the tool D⁶ or the tool D⁷ into alinement with the stock-rod, according as it is desired to turn said rod down to size or to thread the turned-down rod after the turning-down operation has been completed. In the construction shown the several shafts D⁶, of which any suitable number may be employed, according to the capacity of the machine, are arranged in a circle, and their several pinions D⁹ are meshed by a gear E, keyed to a handle-sleeve E', the latter being preferably keyed at e' to the hub e of the gear E and the said sleeve being provided on its inner end with a projecting pin E² to enter one or the

other of two sockets e^2 in the outer face of the stock, as best shown in Figs. 3 and 4 of the drawings. The handle-sleeve E' , with the pin E^2 , may be moved in the direction of length of the shaft A back from the position shown in Fig. 3 to a sufficient extent to free the pin E^2 from the sockets e^2 without moving the gear E out of mesh with the pinions D^6 , and when the sleeve E' has been retracted 10 to such extent it may be turned to turn the gear E to rotate the pinions D^6 and the shafts D^5 to bring either the cutters D^6 or D^7 into alinement with the stock-rods and then be locked in such position by releasing the sleeve E' and permitting the pin E^2 to enter the registering socket e^2 , a spring E^3 being arranged 15 to normally press the sleeve to the position shown in Fig. 3 to cause the pin E^2 to enter one or the other of the sockets e^2 , as will be understood from Figs. 3 and 4 of the drawings.

As shown in Fig. 3, the spring E^3 fits at one end within the outer end of the handle-sleeve E' and abuts at its other end against a collar E^4 , which may be adjusted along the shaft A and secured in any desired position by the set-screw e^4 , as will be understood from Fig. 3 of the drawings.

In operation when the stock-rods have 30 been fed forward to the desired position the tool D, having its turning-down tools D^6 set into alinement with said rods, may be moved forward upon the rods, the latter being rotated by the devices presently described to 35 turn the rods down to the desired form of bolt. The tool D may then be retracted and the devices E and E' operated to adjust the thread-cutting dies D^7 into alinement with the turned-down bolt-blanks and the cutter- 40 head be again fed forward upon the revolving rods to thread the same as desired. The formed bolt or set-screw will then be cut off by the devices which will be described.

The feed-screw F is supported at one end 45 in a bearing f' , which may be mounted on a suitable standard, as shown in Fig. 2, and is driven by means of a friction-coupling arranged at its other end from the shaft A. This coupling is shown in detail in Fig. 3 and 50 includes a socket-section G, secured at g to the end of the shaft A and provided at one end of the sleeve G, the latter being provided at its other end with a tapered socket G' , and the plug-section H keyed at h to the inner 55 end of the screw F and movable along but turning with the said screw, a spring H' being arranged to press the plug H normally into driving feed with the socketed sleeve G, the said spring H' bearing at its outer end against 60 a collar H^2 , which may be adjusted along the feed-screw and secured in any desired adjustment by the screw h^2 in order to adjust the tension of the spring H' to the desired degree. Normally the spring H' presses the 65 plug H into driving contact with the sleeve

G, and said plug may be released by devices operating upon a disk or plate I, which journals at I' upon the plug H, so the latter may turn freely within the plate I', the latter having guide-openings at I^2 for the stock-rods C 70 and being also provided with push-rods I^3 , threaded at i^3 into the plate I, so they may be adjusted in connection therewith, the said push-rods I^3 extending from the coupling-plate I toward the head D and being arranged to be pushed upon by devices presently described in order to disengage the plug H from the sleeve G in the operation of the machine as presently described.

The feed-screw and main shaft, it will be 80 noticed, are in alinement, greatly simplifying the construction of the frame, and the ring I, operated by the push-rods I^3 , is concentric with the said feed-screws and main shaft, as will be understood from the drawings. 85

The stock-rods C are held to a carrier J, preferably by means of screws J' , and the rods extend from the said carrier J through the plate I, thence through guide-tubes K and the rod-clamping devices co-operating 90 with said tubes K, and project through the cutting-off devices L in passing through the cutter-head or disk D^8 , by which they are turned down and threaded in forming the bolts. 95

The carrier J is of a special construction and comprises the body or main plate J^2 , having the central tubular portion or thimble J^3 , sliding along the feed-screw F, and the outer tubular portion J^4 , surrounding the central portion J^3 and receiving the reduced portions J^5 of sleeves J^6 , in which sleeves the stock-rods C are clamped by the screws J' , the sleeves J^6 being provided with annular grooves in which project the inner ends of screws J^7 , by which the sleeves J^6 are secured in the outer tubes J^4 and may be turned freely therein as the stock-rods are rotated in the operation of the invention. By this means the carrier may operate to feed the stock-rods C longitudinally without interfering with the rotation of the stock-rods by the devices presently described. The carrier is provided with a split nut composed of sections M, threaded to engage the screw F 110 and which may be adjusted into mesh with the said screw, as shown in Fig. 13, or outwardly out of mesh with said screw when desired. 115

In order to adjust the nut-sections, I provide a cam-plate M' , (see Fig. 15,) having a central opening M^2 , through which the screw F passes, and provided with a handle M^3 , by which it may be turned from one position to another, with curved slots M^4 , through which the stock-rods C pass, and with cam-slots M^5 , into which project pins M^6 from the nut-section M. 120

It will be noticed that by swinging the plate M' down in the direction of the arrow 130

from the position shown in Fig. 15 the pins M⁵, traveling in the slots M¹⁴, will free the nut-sections M from the screw F. In case the operator should fail to release the nut-sections after the carrier has been fed along the screw F to its full extent I form said screw with its threads tapering out at f, (see Figs. 1, 2, and 3,) so that as the split nut reaches the limit of its movement it will be opened by 5 to the tapered portion of the feed-screw at f to prevent any jamming of the parts.

The guide-tubes K are journaled and turn in a frame N, mounted on the main frame of the machine, said frame N being preferably 15 provided with end plates N' and the guide-tubes K, having a shoulder K' bearing against the outer side of one end plate N' and a nut K² bearing against the outer side of the other end plate N', so the said tubes will be held 20 against lengthwise movement and are free to turn on the said plates N' of the frame N, as will be understood from Fig. 3 of the drawings. These guide-tubes K have bores, preferably circular, through which the stock-rods 25 pass, and on the said tubes K, I key pinions K³, which are meshed by a pinion A' on the shaft A, so the said shaft will turn the guide-tubes K and will thereby turn the stock-rods C when the latter are clamped to the guide-tubes K by the means presently described.

The guide-tubes K are provided beyond the shoulder K' with an externally-threaded portion K⁴, preferably slotted at K⁵ to receive the gripping-blocks O, which project in the 35 slots K⁶ and are thereby keyed to turn with the tube K, as will be understood from Fig. 9 of the drawings. These gripping-blocks O are normally pressed apart by springs O', arranged as shown in Figs. 8, 9, and 10, and are 40 inclined at their opposite ends at O² to engage at one end with inclined bearings at P' in the guide-tube K and at their other ends with the inner tapered ends P' of plugs P, which plugs are threaded into the outer ends 45 of the threaded sleeves Q, which are threaded at one end onto the threaded extension K⁴ of the tubes K and receive the plugs P in their other or outer ends, as best shown in Fig. 8 of the drawings. When these nuts Q are 50 screwed from the position shown in Fig. 8 onto the threaded extension K⁴ of the tube K, they travel to the left, or toward the shoulder K', and as they so travel they carry the screw-plugs P with them, and thereby operate to 55 compress the gripping-blocks O by the action of the tapered inner ends of the plugs P and the tapered surfaces at O² upon the inclined ends of the said gripping-blocks, as will be understood from Fig. 8 of the drawings.

60 For purposes of adjustment I prefer to use the screw-plugs P in securing the tapered surfaces P' for engagement with the outer tapered ends of the gripping-blocks O. In order to turn the screws Q to cause them to 65 travel along the threaded extension K⁴ in one

direction or the other, I provide said nuts Q with pinions Q', which mesh with the internal teeth R' of a gear R, the latter being preferably made in sections, as shown in Fig. 6, for convenience in assembling and being provided on opposite sides of the teeth R' with the face plates or rings R², which project inwardly on opposite sides of the pinions Q', so the gear-wheel R will be caused to travel in the direction of length of the tubes K as the 75 nuts Q screw on and off the extensions K⁴ of the tubes K. The purpose of this is not only to retain the pinions Q' in mesh with the gear R, but also to cause the said gear R as it approaches the frame N in moving to the left 80 from the position shown in Fig. 3 to strike the free ends of the push-rods I' and through said push-rods free the plug-section H of the friction-coupling from engagement with the section G of said coupling, which latter section is secured to the shaft A, while the plug-section is keyed to the feed-screw F, as before described. Ordinarily the nuts Q will 85 revolve with their respective guide-tubes K, and as they so revolve they will turn the gear R with them, the said gear R being normally free to revolve. If, however, the gear R be held from turning, the nuts Q will be locked from turning on the threaded extension K⁴ of the revolving tubes K, and the said nuts will be 90 caused to travel along the threaded extensions K⁴ as the carrier-tubes are revolved, and as the nuts travel to the left from the position shown in Figs. 3 and 8 they will operate upon the gripping-blocks to press the 95 same inwardly and cause them to grip the stock-rods and hold the said rods against endwise movement, the gripping-blocks O being provided in their inner faces with angular grooves O³ to receive the corners of the 100 angular stock-rods, as will be understood from Fig. 9. Thus in this operation it will be noticed that if the gear R be locked from turning such gear will then prevent the nuts Q from turning with the guide-tubes K and 105 the nuts and gear R will be caused to travel to the left from the position shown in Fig. 3, and this movement of the nuts Q to the left will operate to clamp the stock-rods against endwise movement and will also operate to 110 move the gear R to the left and causing said gear R to strike the free ends of the push-rods I' will push the coupling-section H out of 115 engagement with the section G, and so stop the feed-screw from feeding the stock-rods 120 into the machine. I thus provide for locking the stock-rods against endwise movement without interfering with the revolution of said stock-rods by means of the gears A' and K³, which gear the guide-tubes K with 125 the shaft A, as before described.

In locking the gear R from turning I prefer to provide a band S, encircling the said gear R and having projecting ends S' and S², the former being inclined and arranged to be en- 130

gaged by a lever S^3 , pivoted at S^4 and arranged to be swung to the position shown in Fig. 6 to clamp the band S upon the gear R to lock the latter from turning, the lever S^3 being carried by a bracket S^4 from the bed-frame, as shown in Fig. 6 of the drawings. After the stock-rods have been fed to the desired position the parts may be operated, as before described, to clamp the said rods against endwise movement through the guiding-tubes and to detach the feed-screw from the main shaft, after which the projecting ends of the stock-rods may be operated upon by the tools before described to turn down the shanks of the bolts and thread the same as desired, after which the bolts may be cut off from the stock-rods and the machine be operated to feed new lengths of the stock-rods in position to be operated on and the operation repeated from time to time. In feeding new lengths of stock-rods to position for turning down and threading the locking device S should be clamped upon the gear R and the shaft A be driven in the reverse direction to cause the nuts Q to travel back to the position shown in Fig. 3, thus releasing the blocks O from gripping contact with the stock-rods and readjusting the friction-clutch to connect the feed-screw with the shaft A , when the feed-screw will, through the carrier J , feed the rods forward as desired.

After the stock-rods have been fed forward and operated upon by the turning down and threading tools the cut-off devices are operated to cut the bolt from the stock-rod. These devices include, as shown, the tools T , the tool-carrying plate U , and the cam-plate V . The tool-plate U is in the form of a disk supported on standards U' , rising from the bed-frame and provided with inwardly-projecting lugs U^2 , entering slots in the edges of the plate U , as shown in Fig. 17, so the plate U will be held from turning and yet will move along the lugs U^2 in the direction of the shaft A . The purpose of this is to enable the tools to be set forward or toward the head D when it is desired to employ the cutting-off tools for shaping down the throats of the set-screws when the machine is used for making set-screws, the tool-plate and its tools being moved back and forth by the means presently described. The plate Q is provided with openings through which the stock-rods project and with bushings U^3 in said openings and fitting the rods, so the rods will turn freely in the tool-plates U . The cutting-off tool T is held in suitable guides on the plate U , so they may be moved toward and from the respective openings for the passage of the stock-rods, as shown in Fig. 19, and may be moved by the means presently described. To this end the tools T are provided at one side with projecting studs T' , which extend through the slots U^2 in the plate U and thence into cam-slots V' in the tool-setting plate V , so as the said plate V

is turned the tools will be caused to travel toward and from the stock-rods. The plate V turns on the shaft A , being provided in its edges with recesses V^2 , receiving the lugs U^2 , and has a projecting hub V^3 , provided with groove V^4 , receiving a yoke V^5 on a lever V^6 , which is pivoted at V^7 at one end and connected at its other end with a hand-lever V^8 , having a tool V^9 entering detent-sockets V^{10} , by which to hold the lever V^8 and the cutting devices in position to form a throat on a set-screw or to cut off the finished set-screw or bolt as may be desired. It will be noticed the slots V^2 permit the turning of the plate V and the slots in the plate U , receiving the lugs U^2 , permit the travel of said plates U along the lugs U^2 in adjusting the cutting devices back and forth.

The plate V is provided with worm-teeth V^{11} , which mesh with the worm V^{12} on the worm-shaft V^{13} , the latter turning in slotted bearings V^{14} in the standards U' , so the shaft may travel back and forth with the plate V , being carried by means of the bars V^{15} , secured at V^{16} to the cam-plate V and slotted at their lower ends at V^{17} to receive the shaft V^{18} and permit the turning of said shaft in the bars V^{15} and the movement of the said bars along the shaft V^{13} as the cam-plate is turned.

The shaft V^{13} may be turned with a hand-crank V^{18} or by the worm-wheel V^{19} from the feed-shaft B' , the worm-wheel V^{19} being loose on the shaft V^{13} and a clamping-nut V^{20} being provided for clamping the worm-wheel to the shaft when desired. By this means the worm-shaft V^{13} may be operated by hand or by power, as desired.

The tool T is preferably made of the main or intermediate section T^4 and the side sections T^2 and T^3 . The section T^2 has a threaded opening t^2 to receive the screw-stem t' of the stud T' , the main section T^4 has a slot t^4 for the passage of such stem, and the section T^3 has a rabbeted opening t^3 for the passage of the shank t' , as shown in Figs. 20 and 21. By the described construction the tool T may be adjusted to set the intermediate section farther forward or back, as may be desired, and the stud T' may operate as the clamping means for securing the tool-sections in any desired adjustment. The tools T slide in grooves U^4 in the tool-plate U^3 and are held in said grooves by the cap-plates or slides U^{14} , whose inner sides are grooved at U^6 to receive the outer faces of the tool, the said cap-plate U being held by stop-pins U^{15} and guided by the rails U^8 , secured by the screws U^7 . By this construction the tools are securely held in place, so they may freely move back and forth, as desired.

The cap-plate is a cover and guard for the cutter and is held slidably in the guide-rails U^6 , so they can be removed whenever it is desired to apply or remove the cutters.

The cutting ends of the sections T^4 , T^2 , and T^3

T³ of the tool T are formed as best shown in Figs. 19, 21, and 22.

In the operation of the described construction the stock-rods may be fed forward by the carrier J, operated upon by the feed-screw F. When the desired length of rod has been fed through the guide-tubes K to project beyond the said guide-tubes, the holding device or brake S is applied to the gear-wheel R and the nuts Q are caused to travel back on the threaded extensions K⁴ of the tubes K, setting the gripping-blocks into clamping contact with the stock-rods to prevent the same from further endwise movement and the gear R simultaneously uncoupling the feed-screw from the drive-shaft. The head D is then fed forward upon the revolving ends of the stock-rods, first to turn the said rods down to the desired size and then adjusted and fed upon such turned-down ends of the stock-rods to thread the bolts, the ends of the rods entering longitudinal openings d⁹ in the body of the stock D as they pass through the turning-down tool and the threading-dies, as will be understood from Fig. 3 of the drawings. After this the cutting-off devices are adjusted, as before described, to cut off the bolts from the body of the stock-rods.

Having thus described my invention, what I claim as new, and desire to secure by Letters Patent, is—

1. The combination substantially as herein described, of the framing, a carrier for the stock-rods, means for revolving the stock-rods, a feed-screw operating upon the carrier, a drive-shaft and coupling between the shaft and screw, devices for holding the stock-rods against endwise movement, means for operating the said holding devices, and devices operated by said means for releasing the coupling between the shaft and feed-screw.

2. The combination of the tool-head, cutter-heads provided with tools and with shafts journaled in the tool-head, the pinions on said shafts, the gear meshing with said pinions and means for turning said gear and for locking it in its different positions.

3. The combination with the tool-head, and the cutter-heads each having eccentrically-arranged cutters and provided with shafts journaled in the tool-head, of the pinions on the said shafts, the gear meshing with said pinions, the sleeve slidably keyed to the said gear and arranged to operate the same, and a pin carried by the sleeve and arranged to engage a relatively fixed part whereby to lock the gear in its different positions, substantially as set forth.

4. The combination in a machine substantially as described, of the cutting-off tools, a plate carrying the same and slotted in its opposite sides, standards having lugs entering said slots whereby the tool-plate may move along the standards and means for moving

the tool-plate along the standards substantially as set forth.

5. The combination in a machine substantially as described, of the feed-screw, a stock-carrier arranged to be fed by said screw, the main shaft, a coupling between the main shaft and the feed-screw, clamps for holding the stock-rods from longitudinal movement, means for forcing said clamps into engagement with the stock-rods and intermediate devices between the means for operating the clamps and the coupling between the feed-screw and main shaft, substantially as set forth.

6. The combination in a machine substantially as described, of the framing, the main shaft, the rotatable guide-tubes for the stock-rods, gripping-blocks in said tubes, nuts turning on the tubes and arranged to compress the blocks upon the stock-rods, means for turning said nuts into and out of position to compress the gripping-blocks, a carrier for the stock-rods, a feeder for said carrier and intermediate devices between the nuts and the feeder for the carrier whereby the feeder may be thrown out of operation when the nuts are adjusted to position to compress the gripping-blocks, substantially as set forth.

7. The combination in a machine substantially as described of a main shaft, a feed-screw, a carrier for the stock-rods arranged for operation by the feed-screw, guide-tubes arranged to receive the stock-rods, a frame supporting said tubes, means for turning the tubes, whereby to turn the stock-rods, the tools for operating on the stock-rods arranged on the opposite side of the tube-supporting frame from the carrier, means for holding the stock-rods from longitudinal movement arranged between the said frame and the tools for operating on the stock-rods, a coupling between the feed-screw and the main shaft, said coupling being arranged between the tube-supporting frame and the stock-carrier, and rods extending from said coupling through the tube-supporting frame and arranged for operation by the devices for holding the rods from longitudinal movement, substantially as set forth.

8. The combination with the cutting-off tools, and the plate carrying the same and provided in its opposite sides with slots, of standards having lugs entering said slots, whereby the tool-plate may move along the standards, tools movably supported on said tool-plate, a cam-plate to operate in said tools, means for turning the cam-plate, and means for moving the cam-plate and tool-plate along the standards, substantially as set forth.

9. The combination in a machine substantially as described, of the tool-carrying plate, the tools movable along said plate, the cam-plate arranged to operate said tools and provided with a worm-rack, a worm-shaft mesh-

- 6
13. The combination with the rotatable guide-tubes having threaded portions, the gripping-blocks in said threaded portions, nuts turning on the threaded portions and provided with means operative to compress the blocks, and said nuts being provided with pinions, a gear-wheel meshing with said pinions, means whereby the gear-wheel may be held from turning, push-rods arranged to be acted on by said gear-wheel, a feed-screw, a main shaft, a coupling between said screw and shaft, and means connecting said coupling with the push-rods, whereby the latter may be operated by the gear-wheel to release the coupling, the gear-wheel being movable toward the coupling to operate the push-rods, substantially as set forth. 50
10. The combination with the tool-plate and the cam-plate, of the tool composed of an intermediate section having a longitudinal slot, sections on opposite sides of the intermediate section, and the stud passing through said section, and having a threaded stem screwing into one of the sections, said stud passing through the tool-plate into the cam-plate, substantially as set forth. 55
11. The combination with the main shaft, the carrier for the stock-rods, a feed-screw for operating said carrier, a coupling between the feed-screw and the main shaft, a series of rotatable guide-tubes for the stock-rods, gear- 60
- 20
- 25
- 30
- 35
- 40
- 45
14. The combination of the main shaft, the guide-tubes for the stock-rods, provided with pinions, a gear on the main shaft, and meshing with said pinions, whereby to turn the guide-tubes, said tubes being provided with threaded portions, nuts on said threaded portions and provided with pinions, means operated by the travel of said nuts along the threaded portions for clamping the stock-rods against endwise movement, and means whereby the said nuts may be held from movement whereby they will be caused to travel along the threaded portions. 70
15. The combination in an apparatus substantially as described, with the feed-screw, and a carrier operated thereby and arranged to feed the stock-rods, of the main shaft, means for clamping the stock-rods against endwise movement, and means operated from the stock-clamping means for uncoupling the feed-screw from the main shaft when the stock-clamps are thrown into position to grip the stock-rods, the feed-screw being driven by the main shaft, substantially as set forth. 75
12. The combination with rotatable guide-tubes for the stock-rods and having a threaded portion, of gripping-blocks in said threaded portion for holding the stock-rods against endwise movement, nuts turning on said threaded portion and provided with means for compressing the blocks upon the stock-rods, said nuts having pinions, a gear-wheel meshing with said pinions, and turning normally freely with said pinions as the latter are revolved with the guide-tubes, and means for locking said gear from turning, whereby the nuts may be held by their pinions from turning and will be caused to travel along the revolving threading portion, substantially as set forth. 80
16. The combination with the rotatable guide-tubes having threaded portions, the gripping-blocks in said threaded portions, nuts turning on the threaded portions and provided with means operative to compress the blocks, and said nuts being provided with pinions, a gear-wheel meshing with said pinions, means whereby the gear-wheel may be held from turning, push-rods arranged to be acted on by said gear-wheel, a feed-screw, a main shaft, a coupling between said screw and shaft, and means connecting said coupling with the push-rods, whereby the latter may be operated by the gear-wheel to release the coupling, the gear-wheel being movable toward the coupling to operate the push-rods, substantially as set forth. 85

JOSEPH KENNARD KOONS.
